UNITED STATES PATENT OFFICE.

S. ANDRAL KILMER, OF BINGHAMTON, NEW YORK.

RAILROAD-JOINT.

SPECIFICATION forming part of Letters Patent No. 371,688, dated October 18, 1887.

Application filed February 24, 1887. Serial No. 228,752. (No model.)

To all whom it may concern:

Be it known that I, S. ANDRAL KILMER, a citizen of the United States, residing at Binghamton, in the county of Broome and State of New York, have invented certain new and useful Improvements in Railroad-Joints; and I do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 Figure 1 is a perspective view of the device in position. Fig. 2 is a section on line xx , Fig. 1. Fig. 3 is a section on line yy , Fig. 2. Figs. 4, 5, and 6 show three forms of the bolt-protector. Fig. 7 is a side view of the rail, 20 parts broken away to show one of the fish-plates and rollers. Fig. 8 is a detail under view. Fig. 9 is a side view of the outside fish-plate. Fig. 10 is a side view of the inside fish-plate, the foot being removed. Fig. 11 is a 25 top view of the fish-plates, the rails being removed. Fig. 12 is a detail modification in section. Fig. 13 is another detail modification in section. Fig. 14 is another detail modification in section.

30 This invention relates to improvements in the road-beds of railroads, more particularly to the features connected with the construction of the rail joints at the meeting ends of rails.

In railroads as ordinarily constructed it is 35 a matter of common experience that as the rails contract and expand, causing a movement between the fish-plates, the attempted resiliency of the latter does not compensate for the movement. As wear ensues, the bolts are 40 tightened; but withal the fish plates spread and the web of the rails come in contact with the bolts, cutting them in grooves and binding them, so that when the wrench is applied for tightening the fish-plates the bolts crack, the 45 weight of a train breaks them, and accidents occur.

It is the object of one part of this invention to provide the bolts with a protector, which 50 allows the free expansion and contraction of the rails, stiffens the fish-plates, allows heavier ones to be used, and protects the bolts from wear.

By the use of another feature the tendency for pressure at one end of a fish-plate to jump up the other end is avoided.

In the annexed drawings, the letters A A indicate two rails having the meeting ends $a a$, at which are placed the fish-plates, as usual. The fish-plate B has cast with it the foot b at its middle. This foot extends to such a distance each side of the middle line of the fish-plate as to brace the plate strongly. The foot extends out at a right angle to the bottom of the fish-plate and has the spike-holes b' . Rising up from this foot at the exact middle of the 65 fish-plate is the back brace, b^2 , terminated under the flange b^3 on the top of the fish-plate. At each end the foot b has on its underside a dovetail groove, c , which engages a corresponding tongue, c' , upon an under toe, C, the 70 projecting end c^2 of which catches under the end of the rail, as shown in Fig. 8. If desired, however, the foot b need not be used, but it makes a much stronger fish-plate. After the fish-plates are secured in place on the rail, 75 spikes are driven into the holes b' , securing the plate to a cross-tie. The outside fish-plate, D, is also strengthened by a backing, b^4 . The fish-plate B is provided with the due number of rectangular holes d , properly spaced apart 80 for the bolts. These holes are cut entirely through the plate B. The outside fish-plate, D, has the same number of round bolt-holes d' made through it, spaced apart, as are the holes d .

85 On the inside of the fish-plate D and about the holes d' are recesses d^2 , of the same shape and size as the holes d , and they align pair for pair when the fish-plates are in position.

The meeting ends of the rails are provided 90 with rectangular openings a' , both rails together having the same number as there are holes d . The openings a' are of the same depth as that of the holes d , but they are longer than the holes.

95 The letter E represents the bolt-protector. This is preferably a rectangular block having the smooth or unthreaded bore e passing lengthwise through it. This block in cross-section has the area of the holes d and recesses d^2 and fits them. The bore e is of a size for the ordinary bolt, F. After the rails are laid and the fish-plates put into place, the protectors E are slipped through the holes d , open-

ings a' , and rested in the recesses d' . Then the bolts are slipped from the other side through the bores e . A plate, f , is then slipped on, and against this a spring-washer, G , and then 5 the nut H .

On the inside the fish-plates are provided with pockets $k k'$, two for each plate, on each side of the middle, there being one quite close to each side of the middle, and therefore close 10 to the end of each rail. These pockets contain cylindrical rollers K , arranged vertically and loosely in the pockets, fitting the latter snugly. These rollers project beyond the faces of the plates any determinate distance. When 15 the spring-washer hereinafter described is used, these rollers will have their pockets of the same depth throughout.

In Fig. 12 is shown a form by using which the spring-washer can be dispensed with. 20 Here the pockets have bottoms p^2 , which flare outwardly toward the ends of the rails, so that the pockets are deeper away from these ends. As the rails change with the variation of temperature, these rollers move in and out and 25 allow full compensation without affecting the fish-plates.

As thus constructed, the rails have a free play within the fish-plate. The rollers allow of the movement. The bolts are not, under 30 any circumstances, touched by the rails and cannot be cut. The protectors brace the fish-plates. The nuts can be turned on the bolts, taking up wear without danger of breaking the bolts, as they move freely through the 35 protectors. The latter brace the fish-plates, which are bound firmly against the protectors by the bolts. With this construction stronger fish-plates than usual are used. To provide resiliency for them, I employ a novel spring-washer, G . This is a split flat ring, wavy in the direction of its circular length, and having diverging grooves g in each surface at the top of each curve or wave. The effort of the 40 compression to flatten this ring and its resistance consequent upon its construction gives great elasticity, which is imparted to the fish-plates and holds them, though stiffened more than usual, against the variation of the rails under change of temperature. When this 45 joint is to be used upon a curve, the fish-plates are put down practically straight; but the size of the rollers is varied according to the radius of the curve, the position of the rollers in the plates being varied so that a line touching the 50 projecting faces of the rollers would give the desired curve. This feature is clearly indicated in Fig. 11.

In the use of the "bolt-protector" I do not propose to limit myself to a railroad-joint, 55 as it can be used at any place where there is a sliding movement upon a bolt—such, for example, as in bridges, buildings, locomotive-framings, and elsewhere.

If in using this particular feature on a railroad at the joint it should be deemed inadvisable to allow the rail to bear upon the block or protector, the latter could be grooved at top and bottom between the fish-plates. This would keep the rail from striking the protector, while the latter would perform its useful functions and the rail would bear upon the strengthened fish-plates. This form is shown in Fig. 5. As shown in Fig. 6, this protector may have its edges rounded; also, if desired, instead of a separate protector being used 70 with the cut and recessed fish-plates, these plates may be made with each of them provided with one half of the protector and the other plate with the other half, and the two halves coming together, as indicated in Fig. 75 13, at $n n'$, p being the bolt; or the protector may be cast wholly with one fish-plate, as in Fig. 14.

In the present case I make no claim to the friction-rollers and the construction of the 80 fish-plates connected therewith, as the same is the subject of another application.

Having described my invention, what I claim is—

1. The combination of a bolt and its protector, the latter having a smooth bore for the bolt, with a rail or analogous device having for the bolt and its protector a slot which is longer than the cross-section of the protector, as set forth. 90

2. The combination of a bolt and its protector, the latter being a rectangular block and having a smooth bore for the bolt, with a rail or analogous device having for the bolt and its protector a slot which is longer than the cross-section of the protector, as set forth. 100

3. The combination of a bolt and its protector, having a smooth bore for the bolt, with the fish-plates and rails of a railroad-joint, said rails having a slot which is longer than the cross-section of the protector, as set forth. 105

4. The combination of a bolt, its protector having a smooth bore, with the fish-plates and rails of a railroad-joint, one fish-plate having holes corresponding to the size of the protector, the other fish-plate having a bolt-hole and inside a recess corresponding to the hole in the other fish-plate, and the rails an opening of the depth of the hole, but longer, as set forth. 110

5. A fish-plate having the foot extending 115 out from its base, said foot having the separable under toe, as set forth.

In testimony whereof I affix my signature in presence of two witnesses.

S. ANDRAL KILMER.
